MULTIPLE SIDE POCKET BILLFOLD

Emil Karl Renz, Dedham, Mass., assignor, by
mesne assignments, to Debonair, Inc., Boston,
Mass., a corporation of Massachusetts

Application October 11, 1946, Serial No. 702,657

3 Claims. (Cl. 150—38)

1

The present invention relates to improvements in pocket wallets of the type which may be folded on a center line to bring the halves of the outer face or wall on either side of the center line substantially in parallel relation to one another.

In this type of wallet, when it is desired to provide a number of compartments or pockets in addition to the bill fold receptacle or receptacles, due to the wallet construction the wallet may have unnecessary stiffness and bulge at places folded, especially if the wallet has a number of bills and cards. Various means have been taken to avoid this difficulty, among which is the construction shown in my Patent No. 2,366,875 patented January 9, 1945, and the improvement disclosed in my pending application Serial No. 579,957 filed February 27, 1945, now Patent No. 2,439,580, issued April 13, 1948. In the present invention, the construction of this type of wallet is further improved by the construction of the side pockets and the manner and means by which these elements tie in with the stay member and divider. Besides the bill compartment, the wallet of the present invention provides at least two side pockets on each side with a flexible and free coupling of the stay member and divider together and to the wallet.

The present invention will be more fully described in the specification below when taken in connection with the drawings illustrating an embodiment of the same, in which Figs. 1, 2, 3, 4, and 5 show developments of elements of the wallet before being folded and assembled; Figs. 2' and 4' show modifications of elements of Figs. 2 and 4 respectively; and Fig. 5' an assembly of these elements.

Fig. 6 shows the assembly of elements partially completed;

Fig. 7 shows the assembled wallet looking at the inner face with the wallet opened out;

Fig. 8 is a section on the line 8—8 of Fig. 7, and

Fig. 9 is a section on the line 9—9 of Fig. 7.

In the drawings, the outer wall or face 1 is provided with two end flaps 2 and 3 (Fig. 1) which end flaps form the outer faces of side pockets on the inside wall of the pocket and therefore serve as a part of the inner wall of the wallet. Flaps 2 and 3 have a crease line 4 positioned in from the top edge 5 which is the top of the outer wall. Extensions 6 are joined at the crease 4 along the top of the flaps 2 and 3. These extensions are provided with two tabs 7 and 8, the tab 7 pointing inward and upward and the tab 8 being of a T formation and joined

to the extension 6 in the stem of the T. The purpose of the T tab 8 is to lock with the side section 9 in its extension 10. This side section faces on the inner face of the end flap, extending nearer to the central portion of the inside wall of which it forms a part than the end flap to which it is attached. The outer side pocket is in fact formed by the pieces 2 and 9 and the inner side pocket by the side section 9 and the stay member 11 (see Fig. 4) as will be explained later. The extension 10 has a horizontal slot 12 into which the cross portion of the T tab 8 is fitted and locked. The section 9 is on the inside of the flap 2 and the fold line 13 therefore lies over the fold line 4 with the extension 10 folding over opposing the section 9 and the extension 6 lying in face contact with the other face of the extension 10.

The sections 9 and 10 when folded along the line 13 act as a sleeve to receive the stay member 11 while the stay member forms the inside of the half side pocket with the section 9 as the outer face.

It will be noted that the extension 10 has a square cutout section 14, which serves to engage the strap member 15 in the divider piece 16 (see Fig. 5). The stay member 11 and the divider member 16 are linked together by means of the end straps 15 and 17. These end straps are formed with enlarged ends 18 and 19 which engage in the slots 20 and 21 of the stay member 11, which slots are smaller than the end sections 18 and 19, so that the stay member and divider will remain normally joined together. As will be noted in Fig. 4 the slot 20 is located at about the same distance from the base of the recessed square section 22 as the slot 21 is from the end edge 23. In assembling the pieces 11 and 16 together, the straps 15 and 17 are creased along the dotted lines 24 and 25 and are folded over the face of the stay 11 as positioned in Fig. 4. The strap 15 is somewhat narrower than the recessed section 22, so that considerable play in a longitudinal direction is provided between the stay member 11 and the divider 16. When the elements 11 and 16 are assembled, they may be placed in position in assembling the wallet. This position is shown in Fig. 6, in which the stay member 11 lies in front of the divider member 16. The sections 9 and 10 as viewed in Fig. 6 are folded inwardly with the sections 2 and 3 by folding along the fold lines 26 and 27. The sections 10 are then folded downward between the stay member and divider with the cutout sections 14 engaging the straps 15 and 17. These

straps 15 and 17 are permitted sufficient looseness in the recessed locking sections 14, so that both stay and divider may be moved together for a short distance longitudinal of the wallet. Folding the section 10 inward locks the straps 15 and 17 in place so that they do not readily come apart after the wallet has been assembled. As a matter of fact, it is not necessary either to cement or sew any of the pieces together, except for the stitching along the bottom edge as indicated by 29 (Fig. 7) which, of course, stitches together in a single stitching the lower edges of sections 2, 3, and 9 to the back face 1 of the wallet. For this purpose, the bottom margin 30 of the outer wall 1 may be bent up over the lower edges of the pieces 2, 9, and 3 and the stitching may be through stitching from the back to the front of the wallet. The stay member 11 is, of course, free from this stitching.

In the assembled position shown in Fig. 7, the wallet is shown as having one long pocket in which the divider 16 is positioned and two pockets on either side of the center section 28 shown by the dotted line, along which the wallet may be folded together. It will be noted that the upper section 6 with the tabs 7 and 8 is tucked outward and downward providing a finished top edge along the fold crease 4.

In the modification shown in Figures 2', 4' and 5', the divider element may be omitted and the side section 9' corresponding to the section 9 of Figure 2 is provided with a different form of extension member 10'. The slot 12' is in the same position as the slot 12, but a tab 40 is provided extending from the recessed wall of the recess 14' with a T-shaped end 41. The tab 40 is folded on its crease line 42, so that the stay member 11' which is laid over the face of the extension 10' is positioned to have its cut out portion 22' engage the tab 40, the T end of which is tucked in the slot 20'. This assembly is indicated in Figure 5' which shows how the stay member 11' is attached in position to the tab 40 folded inwardly of the section 10'. In this way, the divider may be eliminated without disturbing the individual adjustability of the stay member.

Having now described my invention, I claim:

1. In a wallet of the type described having an outer wall and an inner wall with said inner wall having an inner side pocket formed of a folded pocket member and a stay member extending into the folded pocket member, in combination, a second pocket member shorter in length than said inner side pocket formed as an inward fold flap to said outer wall and having a top extension folded over the inside portion of the inner side pocket member and locked to said inside portion, said top extension comprising a T-shaped tab and a projecting tab member, the former locking

through a slot on said inside portion of said inner side pocket and the latter extending downward to the line of fold of said end inward fold flap into the corner of the wallet, the lower edge 5 of the pocket members and the outer wall being stitched together.

2. In a wallet of the type described having an outer wall and an inner wall with said inner wall being formed of inner side pocket members folded over a stay member bridging the space between said pocket members in combination, said inner side pocket member being an independent piece, a second set of pocket members shorter in length than said inner side pocket formed as end inward fold flaps to said outer wall and having top extensions folded over the inside portion of the inner side pocket members, said inside fold of said inner side pocket having means cooperating with means of said top extension to lock said top extension when folded to said inside fold of said inner side pocket.

3. In a wallet of the type described having an outer wall with folding end extensions, said extensions having top extending folding flaps, an independent section having a fold line dividing it in two parts, said parts being folded in face to face relationship and positioned on the inner side of said extension in face to face relationship therewith, with the top extending flaps folding on its fold line substantially coincident with the fold line of said parts and on the inner side of said folded parts, means interlocking said top extending flap in its folded position with one of said parts, said folding extensions and independent sections forming two side pockets with the former shorter than the latter on the inside of the wallet at each end, the lower edges of which, together with the lower edges of the outer wall are all stitched together.

EMIL KARL RENZ.
